(57) **CLAIM**

We claim the ornamental design for a portable terminal with sensors for recording data of activities, as shown and described.

DESCRIPTION

FIG. 1 is a front, top and left side perspective view of a portable terminal with sensors for recording data of activities showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown in the drawings represent unclaimed portions of the portable terminal with sensors for recording data of activities and form no part of the claimed design.
